CHAIR

Earl C. Booth, Columbus, Ind., assignor to Noblitt-
Sparks Industries, Inc., Columbus, Ind., a cor-
poration of Indiana

Application June 5, 1943, Serial No. 489,732

2 Claims. (Cl. 155—194)

My invention relates to metal chairs and has for its object the production of a metal chair which can be simply and economically manufactured, which can be knocked down and shipped in a compact package, and which can easily be erected.

In carrying out my invention I form the seat and back of the chair as a single sheet-metal stamping, desirably weakened by a transverse row of perforations at the junction of the seat-portion and back-portion and provided around its periphery with a stiffening flange which is interrupted at such line of perforations to permit relative swinging movement of the seat-portion and back-portion. To support the back and seat, and to hold them in the desired angular relationship when the chair is erected, I employ two side members, desirably of metal tubing, which are bent into a general U-shaped form to provide a horizontal base leg adapted to rest on the ground, floor, or other supporting surface, a vertically extending intermediate portion which is secured to the seat at a front corner thereof, and an arm-forming portion which extends rearwardly above the seat and is secured to the chair-back.

The accompanying drawing illustrates my invention: Fig. 1 is a side elevation of an erected chair; Figs. 2 and 3 are plan and side elevations respectively of the unitary seat and back of the chair; and Fig. 4 is a side elevation showing the seat and back collapsed for packaging.

The single stamping of which the seat and back of the chair is formed is illustrated in Figs. 2 and 3. It includes a seat portion 10 and a back portion 11 separated from each other by a transverse line of perforations 12. Surrounding the stamping is a peripheral stiffening flange 13 interrupted on each side of the stamping at the line of perforations, as indicated at 14. Near the front corners of the seat portion 10, the stamping is formed with generally semi-circular indentations 16, and similar indentations 17 are provided at a point intermediate the length of the back portion 11.

The precise form given the seat portion and the back portion is a matter of design and may vary considerably.

In addition to the stamping 10—11, the chair includes a pair of side members 20 each of which is desirably formed of metal tubing bent into the general form of a U to provide a base leg 21, a vertical leg 22, and an upper leg 23. The vertical leg 22 of each of the side members 20 is received in one of the indentations 16 at a front corner of the seat, while the rear end of the

upper leg 23 is received and secured in one of the indentations 17. In the particular structure shown in the drawing, the attachment of each vertical leg 22 to the seat 10 is effected through the medium of U bolts 25 which surround the leg 22 and pass through the flange 13. The rear end of each upper leg 23 is secured in its associated indentation 17 by means of a bolt 26 which extends through such upper leg and through the flange 13. Desirably, the chair includes a stretcher 27 which extends between and is secured to the base legs 21 of the two side members 20.

The stamping constituting the back and seat of the chair is formed as a single stamping, and is painted or otherwise finished in any desired manner. Prior to shipment, the back portion 11 may be folded over the seat portion 10 about the line of perforations 12, as indicated in Fig. 4, thus reducing materially the size of the package needed to contain the chair-parts. When the chair is to be erected, the back portion 11 is swung about the line of perforations 12 to a position approximately perpendicular with the seat portion 10, and the side members 20 are then applied. The interruption of the flange 13 at the line of perforations 12 permits the relative swinging movement of the seat portion and back portion.

The line of perforations 12 has a double function. In the first place, such perforations facilitate bending of the stamping 10—11 both into and out of the collapsed condition illustrated in Fig. 4. In the second place, in the completed chair, such perforations provide for the drainage of any water that might otherwise collect in the chair at the junction of the seat and back.

I claim as my invention:

1. In a chair, a single sheet-metal stamping having a seat-portion and a back-portion, said stamping being provided with a transverse row of perforations at the junction of the seat-portion and back-portion and with a peripheral flange interrupted at the ends of said row of perforations to permit relative angular movement of the two stamping-portions about such line of perforations, and a pair of side members disposed at the sides of and supporting said stamping, each of said side members comprising a continuous tube bent into a general U-shape to provide a horizontal base leg, a vertical leg, and an upper leg, said vertical leg being connected to said seat portion near a front corner thereof and said upper leg being connected to said back-portion at a point above said seat-portion.

2. In a chair, a single sheet-metal stamping having a seat-portion and a back-portion, said stamping being provided with a transverse row of perforations at the junction of the seat-portion and back-portion and with a peripheral flange interrupted at the ends of said row of perforations to permit relative angular movement of the two stamping-portions about such line of per-

forations, and means for holding said seat-portion and back-portion in predetermined angular relationship, said means comprising a pair of members each secured to said seat-portion and back-portion at points spaced from said line of perforations.

EARL C. BOOTH.
